GUIDANCE CONTROL FOR MISSILE
Royal Weller, Silver Spring, Md.
(Rochester, N.Y.)
Filed June 3, 1949, Ser. No. 97,061
12 Claims. (Cl. 244—14)
(Granted under Title 35, U.S. Code (1952), sec. 266)

The present invention relates to guided missiles and more particularly to a signal transmitting and receiving system for performing a control function thereon such, for example, as a steering operation effective to change the course of the missiles as they reach a predetermined zone in the trajectory thereof thereby to more accurately direct the missiles toward the target.

The present invention in a preferred embodiment thereof provides a clock-driven arrangement for tuning a radio receiver to receive a signal comprising progressively different frequencies during the flight of a missile. In this manner a plurality of missiles may be launched at different times and only those launched at a certain time will be deflected from the original trajectory by a signal of a selected frequency. In other words, all of the launched missiles will be controllable by a signal of a certain frequency when they have travelled a certain period of time from the time of launching.

An object of the present invention is to provide a new and improved arrangement for changing the direction of flight of a missile to meet a changed target condition.

Another object is to provide apparatus for changing the course of a missile in flight without influencing other missiles launched before or after the launching of the instant missile.

Still another object is to provide apparatus for changing the trajectory of a missile in flight having the qualities of simplicity and ruggedness.

Other objects and many of the attendant advantages of this invention will be readily appreciated as the same becomes better understood by reference to the following detailed description when considered in connection with the accompanying drawings, wherein:

FIG. 1 is a diagrammatic side elevation of a missile in accordance with the present invention, parts being broken away;

FIG. 2 is a diagram of the control circuit therefor and associated apparatus;

FIG. 3 is a diagram of a signal transmitting apparatus for use with the present invention;

FIG. 4 is a diagram of a modified form of the control circuit;

FIG. 5 is a diagram of a transmitter for use with the missile of FIG. 1.

Referring more particularly to the drawings in which like numerals indicate like parts throughout the several views there is illustrated in FIG. 1 a missile 10 having a casing composed of a pair of portions 11 and 12. The portion 11, in the present instance, is employed as a ground for the radio receiver of a control mechanism 13 contained therein, while portion 12 serves as the antenna therefor. The portions 11 and 12 are suitably insulated from each other in any well-known manner as by an insulating band 14. An explosive deflecting charge 15 is mounted in one side of the portion 11 and is arranged to be operated by mechanism 13 under conditions to be hereinafter more fully described.

As indicated in FIG. 2 the mechanism 13 comprises a radio receiver 16 which is grounded to portion 11 of the casing 10 and has its antenna lead connected to portion 12 of the casing. Arranged in the tuning circuit 17 of receiver 16 is a variable condenser 18 driven by a clock 19, the condenser being arranged to progressively

2

vary its capacity during the flight of the missile. In this manner the receiver 16 will be tuned to receive a radio signal comprising any one of several possible, continually changing frequencies at any point in the trajectory of the missile. It is to be understood that the clock 19 is provided with a starter mechanism of any well-known variety which will operate to start the clock at the instant of launching of the missile 10. It will thus be seen that the receiver will be tuned to receive a control signal of a certain frequency at only a small fractional or incremental portion of the trajectory and will be tuned to receive a plurality of progressively different frequencies throughout the flight respectively corresponding to other small fractional portions of the trajectory. The missile, 15 thus may be controlled at any point in its flight by a control signal of a frequency which matches the tuned frequency of the receiver controlled by the instant setting of the variable condenser and corresponding to the instant position of the missile. It is also apparent that other 20 missiles in flight which were launched either before or after the instant missile will not be affected at this time by the signal for controlling the aforescribed missile, for the reason that the control signal is of short duration and the receivers of the other missiles are tuned at this 25 instant to different frequencies corresponding respectively to their positions in their trajectories at the time the signal is transmitted.

In order to provide for firing the charge 15 a relay 21 has its operating coil 22 in a circuit 23 arranged to 30 be energized at the instant a signal of the proper frequency is received by the radio receiver 16. When coil 22 is energized make contact 24 is brought into circuit closing position against contact 25 thus closing a control circuit 30 including a source of power BA connected to 35 make contact 24 through contact 25 to an electroresponsive detonator 26 or other means for firing deflecting charge 15 and thence to source of power BA.

The particular missile referred to herein is of the spinning type and in altering the trajectory thereof it is 40 possible to improve the target impact probability of the missile whereas no such possibility would exist if the target should change course and the missile were restricted to its initial trajectory.

FIG. 3 illustrates in diagrammatic form a transmitter suitable for use with the present invention which comprises a transmitter 27 having associated therewith a selective frequency source 28 whereby signals of any desired frequency may be selected and transmitted to the missile at any time during the flight thereof.

A modification of the arrangement for progressively selecting the receivable signal frequencies during the flight of the missile is illustrated in diagrammatic form in FIG. 4. A clock 29 is provided which is started as the missile is launched. The clock 29 drives a rotatable brush contact arm 31 having an elongated brush 32. A plurality of extendable contact rods 33 are arranged in radially spaced relation around the path of travel of the contact arm 31 and normally spaced therefrom. The contact rods 33 are yieldably held in their normal position preferably by means of springs 34. Extensions 35 of contact rods are employed as movable cores for the solenoid coils 36. A band-pass filter circuit is indicated at 37, it being understood that there is included therein a plurality of filters each of which is tuned to a different frequency to control a selected one of the solenoid coils 36. A receiver 38 as illustrated in FIG. 4 is provided for the reception of signals as in the preferred form of the invention.

In operation a signal of a selected frequency is received by the receiver 38. The signal is passed from the receiver to the band-pass filters 37 wherein the filter tuned to pass the particular frequency of the instant signal

energizes the solenoid coil connected thereto which moves the contact rod associated therewith into contact with the brush 32 of a selected missile. It will thus be seen that brush 32 will be driven by the clock during the entire time of flight and will be progressively adjacent each of the different contact rods at certain intervals of time after the launching of the missile and only those missiles which are within the incremental portion of their respective trajectories corresponding to the particular frequency transmitted from the transmitting station will have their brushes 32 in position to be contacted by the selected contact rods and their steering charges fired thereby. The corresponding contact rods of other missiles which were fired from a gun at different times operate in response to this signal but without effect as their brushes are not in position to be contacted thereby. When the signal ceases the brushes are restored to their initial positions by their springs 34.

As illustrated in FIG. 5 a transmitter 39 is arranged for use with the control mechanism of FIG. 2 or the modified form of FIG. 4 and includes a plurality of signal sources 41, 42, 43, 44 and 45, each of which is tuned to produce a different frequency such, for example, as 20, 30, 40, 50 and 60 kilocycles, respectively. It is, of course, understood that any number of signal sources and any number of solenoid coils may be employed depending on the length of time of the flight of the missile and the amount of changes in frequency desired. In the illustrative embodiment of FIG. 5 a plurality of switches 46, 47, 48, 49, and 51 respectively are employed to select the desired frequency, the switches being marked 4, 8, 12, 16 and 20 seconds, respectively, if desired, in order to assist the operator in selecting the proper switch for operation of the correcting apparatus of a given missile, such markings indicating the number of elapsed seconds of time after the launching of the missile at which time the switches are to be operated.

When one of the solenoid coils is energized and the contact rod 33 associated therewith moves into engagement with brush 32 it will be seen that a trajectory correcting circuit 52 comprising one of the contact rods 33, battery BA1, detonator 26, contact arm 31, and brush 32 will be energized while the brush is in contact with the extended rod 33, thus firing the correcting charge. It will be understood that if the instant missile receives a signal for a certain frequency before or after the brush 32 is in the corresponding position the circuit 52 will not be energized, thus only the missile or missiles launched at a certain time will be affected by any one signal.

As indicated in FIG. 4 the contact assemblies are generally indicated by the letters A, B, C, D and E which in the present instance are influenced or operated by signals of 20, 30, 40, 50 and 60 kilocycles respectively, to correspond with the signals of the transmitter 39.

It will be apparent from the foregoing description that there has been provided apparatus whereby missiles may be controlled by an operator selectively at will while the missiles are in flight course thereof to meet changing positions of the target or for other reasons.

While the invention has been described with particularity with respect to a projectile, it is not so limited as the term missile as employed herein is intended to include other missile weapons such, for example, as rockets and bombs and the invention, therefore, is also suitable for use with spin type rockets, bombs and the like or any other type of missile in which it is desired to change the course thereof during flight.

Obviously many modifications and variations of the present invention are possible in the light of the above teachings. It is therefore to be understood that within the scope of the appended claims the invention may be practiced otherwise than as specifically described.

The invention described herein may be manufactured and used by or for the Government of the United States

of America for governmental purposes without the payment of any royalties thereon or therefor.

What is claimed as new and desired to be secured by Letters Patent of the United States is:

- 5 1. Apparatus for altering the trajectory of a missile comprising, a clock arranged to be started as the missile is launched, a selector mechanism having a brush rotated by said clock and a plurality of normally and yieldably retracted radially arranged contact members, said contact members being arranged to be contacted when in an extended position by the brush member as it rotates, a plurality of actuating coils individual to said contact members for moving the contact members from the retracted to the extended position, a plurality of band-pass filters of different values for controlling the operating frequency of the actuating coils and operatively connected thereto for energizing a selected coil when a matching frequency is received, and a radio receiver in the missile for receiving said frequencies.
- 10 2. Apparatus for changing the trajectory of a missile in flight comprising, a transmitter under the control of an operator and having means for transmitting signals of different selected fixed frequencies, a receiver in said missile for receiving said signals, a clock constructed and arranged to be started as the missile is launched, tuning means continuously driven by said clock for adjusting said receiver continuously and progressively to receive a different one of said signals during each of a plurality of successive periods of time after the launching of the missile whereby a transmitted signal of a selected frequency may be received by the receiver only during a certain period of time after the launching of the missile, an explosive steering charge carried by the missile, and circuit closing means operated by said receiver for firing said charge when said signal of selected frequency is received during the period of time when the receiver is tuned to receive said frequency.
- 15 3. Apparatus for changing the trajectory of a missile in flight comprising, a clock in said missile arranged to be started as the missile is launched, a radio receiver carried by the missile, frequency tuning apparatus driven by said clock and operatively connected to said receiver for continuously and progressively varying the signal frequency which the receiver is adapted to receive whereby the receiver is tuned to receive certain signals, each of a different frequency only at certain periods of time during the flight of the missile, an explosive steering charge, and means controlled by said receiver for exploding said charge when the receiver receives a signal of a frequency in matching relation to the period of time during which it is received.
- 20 4. In apparatus for changing the trajectory of a missile in flight comprising, a clock arranged to be started as the missile is launched, a variable condenser continuously driven by said clock and arranged in the tuning circuit of a radio receiver whereby the receivable frequency of the receiver is progressively and continuously changed during the flight of the missile, an explosive steering charge, and circuit closing means operatively connected to said receiver for exploding said charge when the condenser is tuned to the frequency of a transmitted signal.
- 25 5. In a missile comprising a casing having a pair of electrically conducting sections insulated one from the other, a radio receiver mounted within said casing, one of said sections being operatively connected to said receiver to provide an antenna therefor, the other of said sections being operatively connected to said receiver to provide a ground therefor, a clock in said casing arranged to be started as the missile is launched, a tuning mechanism for the receiver arranged to be driven continuously by said clock at a predetermined rate and to continuously and progressively change the frequency receivable by said receiver during the flight of the missile, an explosive steering charge arranged to exhaust at one side of the

- 75

casing, and means controlled by said receiver for firing said steering charge when the receiver receives a signal corresponding in frequency to the tuned frequency thereof.

6. An apparatus of the character disclosed for changing the trajectory of a missile comprising, a radio receiver carried by the missile, means for continuously and progressively changing the tuning of said receiver at a predetermined rate while the missile is in flight, means for setting the tuning means in operation as the missile starts on said flight, an explosive steering charge carried by the missile and adapted to exhaust therefrom laterally with respect to the line of flight, and means operatively connected to said receiver and controlled thereby for firing said charge when the receiver receives a radio signal to which it is tuned.

7. In a system for altering the course of a projectile, in combination, a transmitting station having means for transmitting radio signals selectively of different fixed frequencies, each of said signals having a frequency corresponding to a different incremental fractional portion of the trajectory of the projectile, a radio receiver carried by said projectile, means for continuously and progressively changing the tuning of said receiver at a predetermined fixed rate during the flight of the projectile whereby the receiver is responsive to a selected signal from said transmitting station during a selected portion of said trajectory corresponding thereto, an explosive steering charge carried by the projectile and arranged to exhaust from one side thereof as the charge is fired, and means including an electro-responsive detonator operatively connected to said receiver and controlled thereby for exploding said charge as a signal is received by the receiver.

8. In a system of the character disclosed for changing the trajectory of a missile in flight, in combination, a source of radio signals of fixed frequency at a control station, means for initiating radio transmission of said signals at a predetermined interval of time after the projectile has been fired from a gun, radio receiving means on the projectile, means carried by the projectile for continuously and progressively changing the tuning of said receiver at a rate proportional to the distance traveled by the projectile during flight thereby to maintain correlative relation between the instant position of the projectile and the signal frequency received by said receiver, an explosive deflecting charge carried by the projectile and adapted to exhaust radially in one direction from the axis thereof, and means including an electro-responsive detonator controlled by said receiver for ex-

ploding said charge when a signal is received from the control station corresponding to the instant frequency of the receiver to which the receiver is tuned.

9. In a system for selecting a missile from a group of missiles in flight and fired from a gun in successive order, in combination, a plurality of tuned radio receivers respectively carried by the missiles, means on each missile for continuously and progressively changing the tuning of the receiver during the flight of the missile, means at a control station for suddenly transmitting a radio signal corresponding in frequency to the instant tuned frequency of a missile to be selected, an explosive steering charge on each of the missiles, and means for firing said charge as a signal is received by the receiver.

15 10. A radio controlled missile of the character disclosed comprising a tuned radio receiver, a control circuit connected to said receiver and rendered effective as a signal is received by the receiver, and means for continuously and progressively changing the tuning of the receiver during flight of the missile whereby the missile is controlled by a radio signal matching in frequency the instant tuned frequency of the receiver.

11. A claim according to claim 10 and including means for initiating operation of the tuning means at the instant the missile is in flight.

25 12. A selective system for the remote control of missiles in flight, each of said missiles having a tuned radio receiver carried thereby, means for changing the tuning of said receiver continuously and progressively at a predetermined rate during said flight, a control circuit operatively connected to said receiver and rendered effective as a signal is received by the receiver, means for setting said tuning means in operation as the flight is started, and means at a control station for transmitting a radio 30 35 impulse signal of a frequency corresponding to the instant tuned frequency of one of said receivers whereby the missile carrying said one of the receivers is selected for control from a plurality of said missiles launched in flight in successive order.
